UNITED STATES PATENT OFFICE.

HARRY A. STONE, OF NEW YORK, N. Y., ASSIGNOR TO FOLDING-STAND COMPANY, INC., OF NEW YORK, N. Y., A CORPORATION OF NEW YORK.

FOLDING TYPE-WRITER SUPPORT.

1,112,944.

Specification of Letters Patent.

Patented Oct. 6, 1914.

Application filed May 14, 1913. Serial No. 767,692.

To all whom it may concern:

Be it known that I, HARRY A. STONE, a citizen of the United States, residing at New York, county of New York, and State of New York, have invented certain new and useful Improvements in Folding Type-Writer Supports, of which the following is a specification.

This invention relates to folding type-writer supports.

The object of the present invention is the provision of an inexpensive, simple, light, strong and durable folding support of improved construction adapted for attachment to any typewriter, particularly those known as portable typewriters, which will be so constructed and combined with the typewriter that it can be folded against the base of the typewriter when not wanted for use as a typewriter support and will then permit the typewriter to be placed upon any other support, table or desk.

Another object of the invention is the provision of a folding typewriter support of such novel construction and combined with the typewriter in such new manner that it may be extended and used as a typewriter support or table or folded and then used as a base support for the typewriter, permitting the latter to be placed upon any ordinary table, desk or support for usual operation.

Another object of the invention is to provide, in combination with a typewriter, an attached foldable support or table therefor, thereby providing a self-contained typewriter and table and obviating the necessity of employing any extraneous table, desk or support for the typewriter when it is to be used.

The invention consists, first, of an improved foldable typewriter support combined with a typewriter and self-contained therewith; second, the provision of an improved foldable typewriter support combined with a typewriter and adapted to fold into such form and arrangement that it will constitute a sub-base for the typewriter and permit the latter to be either supported direct on an ordinary table or desk or to be supported solely by the present improved support; third, in the improved foldable typewriter support having devices which, when the support is folded to constitute a sub-base for the typewriter to which it is

connected, constitute supporting feet for the typewriter; fourth, in the improved foldable typewriter support and its manner of attachment or connection to a typewriter; fifth, in the complete foldable typewriter support and its combination with a typewriter to which it is attached, as fully set forth hereinafter.

In the accompanying drawings:—Figure 1 is a rear perspective view of the invention, the typewriter being shown in dotted lines to better illustrate the manner of attachment of the support thereto; Fig. 2, a bottom view of the typewriter frame and the foldable support, the latter being folded and in position to constitute a sub-base for the typewriter; and Fig. 3, a detail view of one of the joints connecting a supporting leg with the typewriter.

The support is preferably of tripod form, but the legs 1 which may be of any usual or preferred telescopic construction, have no head or top, as usual with tripods but, instead, they are directly connected to the frame 2 of the typewriter so as to constitute, in connection therewith, a self-contained typewriter and stand or support. The telescopic legs 1 are adapted to collapse one within the other so that when collapsed they are no longer than the upper leg sections 1^a, Fig. 2.

To maintain the legs 1 in the spread position of Fig. 1, when the support is used, I provide folding braces 3 which are preferably composed of sections having the joint 4, but I do not limit myself to these particular braces, nor to employing articulated or jointed braces. The braces 3 are pivoted or jointed at 5 to the respective legs, each leg having a brace pivoted thereto and also being provided with a pin or other suitable connecting means 6 to engage the hooked or otherwise constructed free end 7 of a brace which is pivoted to another of the legs. The construction 6, 7, is for the purpose of providing a detachable joint and this may be varied as desired. If preferred, a latch can be employed at this point to prevent accidental disconnection of the leg and free end of the brace.

Two of the upper leg sections 1^a are provided with feet 8 which may be in the form of balls or spheres or as protuberances, these parts being preferably of cushion material such as rubber, and they are designed to

constitute cushion feet for the typewriter 2 when the typewriter support is folded, as shown in Fig. 2, thereby obviating the necessity of providing the usual cushion feet on the typewriter itself. When folded as shown in Fig. 2, however the feet 8 may be constructed, they will be arranged so that they will project downwardly from the typewriter frame and form supporting feet for it when it is placed on a table or desk.

The leg sections 1^a are connected to the frame 2 by joints 9 to permit the legs 1, after telescoping, to be folded against the bottom of the typewriter and to constitute a sub-base therefor. I prefer to have these joints in the form of the usual ball and socket joint, either member of which may be attached to the frame 2. In the form shown in the drawings, the cup member is attached to frame 2 by any suitable fastenings 10 such as screws.

The frame 2 carries fasteners 11 to engage the legs when folded. These fasteners may be of any preferred form; those shown are double spring clips between the members of which the leg is snapped. Any fastener or means which will hold the collapsed or folded legs and braces against lateral swinging when used as a sub-base, as shown in Fig. 2, may be employed.

The support may be attached to the typewriter when the latter is manufactured or may be subsequently applied and it may be made detachable, if desired.

In connection with the typewriter it constitutes a self-contained support which may be used as a table or stand for supporting the typewriter, as shown in Fig. 1, or for folding to then constitute a sub-base for the typewriter, as shown in Fig. 2, permitting the latter to be placed upon any table or desk.

Assuming that the support is in the extended condition shown in Fig. 1, and it is

desired to fold it, the legs 1 are telescoped into the leg sections 1^a, the braces 3 having first been detached at 6, 7. The braces are then folded to lie alongside of the leg sections 1^a. The parts are then folded flat against the bottom of the typewriter frame 2 and secured by the catches or fasteners 11, as shown in Fig. 2, whereupon the feet 8 are lowermost and constitute supporting feet for the typewriter, permitting the latter to be placed upon any desk or table.

In reciting my invention in this specification and the appended claim as being combined with a typewriter, I do not thereby intend to restrict it to use only with a typewriter, as it may be combined with any other machine used for printing characters and, indeed, it may be combined with other devices which require a support during use or operation.

Having thus described my invention, what I claim as new and desire to secure by Letters Patent, is:—

The combination with an object, of a foldable support attached thereto and portable therewith, composed of independent single legs which are independently jointed to the object and adapted to independently fold beneath said object to constitute a sub-base therefor, feet carried by, and projecting from the sides of, said legs, fastening devices for securing the legs in folded condition under said object, and braces jointed to certain of the legs and detachably connected to others of the legs, said braces being foldable alongside of the legs to which they are jointed and foldable with the said legs under the object.

In testimony whereof, I hereunto affix my signature in presence of two witnesses.

HARRY A. STONE.
